Patented Jan. 18, 1916.

UNITED STATES PATENT OFFICE.

FRANK SPURR, OF ST. PAUL, MINNESOTA.

LIP-RETRACTOR.

1,168,574.

Specification of Letters Patent. Patented Jan. 18, 1916.

Application filed March 20, 1915. Serial No. 15,779.

To all whom it may concern:

Be it known that I, FRANK SPURR, a citizen of the United States, residing at St. Paul, in the county of Ramsey and State of 5 Minnesota, have invented a new and useful Improvement in Lip-Retractors, of which the following is a specification.

This invention has for its object the production of a dental appliance, which is use- 10 ful in treatment and surgical work com- monly called oral surgery.

Since the advent of local anesthesia and the perfection of technic in dental practice, it has become necessary to hold the lips of 15 the patient distended so that the practitioner can properly treat and operate upon the diseased part of the teeth or gums, and it has been common practice to employ an 20 assistant for holding the lips distended. By 25 the use of my invention the employment of an assistant is unnecessary and the lips are held widely distended in the most effective manner to suit the requirements and make the work less irksome to the surgeon. In 30 the treatment of pyorrhea, abscesses and other operations involving a number of teeth, my invention is of consequent service and meets all requirements of the case giving the operator full access to the area in- 35 volved with better light and a better view than is obtained in any other way. There is nothing angular about the portion of the appliance catching hold of the lips or cheek to cause irritation or inconvenience, and the 40 parts of the invention are thoroughly sanitary by being readily sterilized from time to time without deterioration. The construction also permits of the invention being 45 easily adjusted and applied in use in 40 substantially any position and at substan- tially any angle desired without inconven- ience to the operator.

In the accompanying drawing forming part of this specification, Figure 1 is a per- 45 spective of my invention illustrated applied in use to the head of a patient; Fig. 2 is a perspective of my invention removed from the head of a patient; Fig. 3 is an edge elevation of a detail of the head band; Fig. 50 4 is a section taken on the line X—X of Fig. 3; Fig. 5 is a perspective of a detail of the lower lip retracting element; Fig. 6 is a perspective of a detail showing a manner in which the lip retracting elements can both

be used to hold one of the lips, and Fig. 7 55 is a section of an alternative construction of my invention.

In the drawing A indicates a flexible band made of thin material and having a broad bearing surface arranged across the forehead of the patient. The band tapers toward its ends and the ends are provided at the sides of the head of the patient with studs 1 to which the ends of a strap 2 passing around the back of the head are secured 60 to hold the band firmly on the forehead. The strap 2 is provided with series of perforations 3 and a clip 4 through which the studs engage, so as to selectively hold the strap at proper length. When desired the 65 strap can be provided between its ends with a buckle 5, by which the length of the strap can also be lengthened or shortened, so that it is not necessary that the ends of the strap project beyond the studs to which they are 70 fastened. Mounted upon the face of the band and extending longitudinally thereof is a guide or track element 6, said guide being secured by soldering or other suitable means 75 longitudinally on the band leaving its longitudinal edges 7 projecting freely and over which the base 8 of a clamp is engaged freely to slide longitudinally on the guide by turned-in hooks 9. The clamp base 8 is formed with a threaded stud bolt 10 through 80 the body of which the shank 11 of a set screw passes longitudinally and is in threaded engagement, said body being formed with a knurled head 12 by which it can be turned 85 and its inner end adapted to bind against 90 the guide when the shank 11 is set by turning downwardly. The clamp base is thus held in longitudinally selected position on the guide over the forehead of the patient. Mounted upon the shank 10 are two disks 13 95 and 14 engaged to turn together, but free to be moved apart without disengagement by pins 15 on one member working freely in corresponding openings 16 in the other member. These disks are adapted to clamp 100 a pair of upper and lower lip retracting elements B and C between them by a set nut 19, which is threaded over the threaded portion of the stud bolt 10.

The upper and lower lip retracting ele- 105 ments consist of a pair of arms 17 and 18, each of which is bowed outwardly between its ends, the arm 17 being formed with a

hook 20 on its lower end, over which an upper lip retracting bail D is secured. The lower end of the lower lip retracting arm 18 is provided with a laterally extending member 22 in the form of an independent arm shaped on one end with a collar 23 embracing the arm 18. This collar is clamped to the arm 18 by a binding screw 24 threaded into said arm and passing through a slot 25 in either side of the collar. The free end of the arm 22 carries a binding screw 26 below which a lower lip retracting bail E is rigidly secured at any angle laterally desired. The adjacent faces of the disks 13 and 14 are formed with corresponding channels 28 through which the arms 17 and 18 pass, the depth of said channels being only sufficient to admit the arms and prevent them from moving longitudinally out of a defined path, but nevertheless causing the disks to clamp the arms in selected position when the set nut 19 is turned down tightly. The upper lip retracting bail is in the form of a single loop of wire bent into an up and inturned broad hook portion 29, which engages below the upper lip and formed with an upwardly extending shank 30, which freely engages over the hook 20, whereby the upper lip retracting bail is suspended freely, so as to engage the upper lip of the patient with the least amount of irritation. The lower lip retracting bail E consists of a single loop of wire bent into a down and inturned hook portion 31 presenting a broad bearing surface, and formed with an outwardly and downwardly extending shank 32, engaging below the binding screw 26 by which the bail is held rigidly upon the arm 22.

40 In use the band A is strapped over the forehead of the patient with the arms 17 and 18 depending therefrom while held between the binding disks 13 and 14. These arms are then adjusted with the bails D and E respectively engaged over and holding the lips of the patient distended wide apart. When adjusted into position so that the lips are spread from over the area desired, the set nut 19 is turned down tightly upon the disks, thus clamping the disks over the arms 17 and 18 and holding the bails with the lips in retracted position. The arms 17 and 18 it will be noted can be placed, so as not to obstruct the area immediately 45 over the space between the retracted portion of the lips, which might otherwise impair the operator's view and access to the teeth or diseased part. When desired the adjacent faces of the disks 13 and 14 can be knurled 50 as indicated in Fig. 7 and grooves 28 not employed, the arms 17 and 18 being clamped between said knurled faces at any lateral angle desired, which the grooves 28 would otherwise prevent. The arms 17 and 18 being bowed outwardly between their respec-

tive ends cause the arms to more closely conform with the curvature and irregularities of the face.

When desired this invention either when slightly modified or in the form described can be employed for holding the sides of a cut or the lids of an eye spread and I desire to have it understood that the invention is not confined in use for holding the lips apart. The arms 17 and 18 can also be employed to hold the bails so that both will engage and hold an upper lip widely distended. This use of the arms is illustrated in Fig. 6, the arm 18 being clamped to the band between the disks 13 and 14 and the other arm 17 held either in parallel position or at an angle by the arm 22 which is secured to the upper end of arm 18 by the collar 23 and to the upper end of arm 17 by the binding screw 24 engaging in the notch 35 in arm 17. In this position the bail D is hung from the hook 20 on arm 17 and the bail E secured in depending position from arm 18 by binding screw 24. The arm 22 it will be noted is reversible so that the arms 17 and 18 can be changed in position either to the right or left hand side.

In accordance with the patent statutes, I have described the principles of operation of my invention together with the apparatus which I now consider to represent the best embodiment thereof, but I desire to have it understood that the construction shown is only illustrative and that the invention can be carried out by other means and applied to uses other than those above set forth within the scope of the following claims.

Having described my invention, what I claim as new and desire to protect by Letters Patent is:—

1. A lip retractor, comprising, in combination, a head band to be secured over the forehead of a patient, and having a guide extending longitudinally thereof, a clamping element mounted upon and secured to said guide, a pair of arms secured longitudinally thereof by said clamp depending from said guide, and bars carried by the lower portions of said arms and engaging the upper and lower lips of the patient to hold the lips distended apart.

2. A lip retractor, comprising, in combination, a head band to be mounted on the forehead of a patient to form a supporting element, an arm attached to said supporting element and depending therefrom, and a bail carried by said arm and engaging the lip of the patient to hold the lip in distended position.

3. A lip retractor, comprising, in combination, a supporting element adapted to be fastened about the head of a patient, a supporting arm extending from said supporting element, means for attaching said supporting arm to said supporting element, and

means detachably carried by said arm for engaging and holding a lip of the patient distended.

4. A lip retractor, comprising, in combination, a head band extending over the forehead of a patient and having a guide extending longitudinally thereof, a supporting element slidably carried by said guide, means for fastening said supporting element in position upon said guide, a pair of arms depending from said supporting element, extensible means for fastening said arms in different extended positions, to said supporting element, and bails carried by the extending ends of said arms and engaging the upper and lower lips of the patient to hold them spread apart.

5. A lip retractor, comprising, in combination, a head band extending over the forehead of a patient having a guide extending longitudinally thereof, a clamp slidably mounted upon and adapted to be secured to said guide, an arm longitudinally slidably upon and adapted to be secured to said clamp 25 and a bail carried by said arm having a hook portion forming a broad bearing surface and a shank portion by which the bail is secured to said arm, said bail being formed by a loop of wire.

30 6. A lip retractor comprising a supporting element to be fastened about the head of a patient, and coöperating elements attached to and depending from said supporting element to engage and hold the lips in distended position.

35 7. A lip retractor comprising a supporting element to be fastened about the head of a patient, and coöperating elements adjustably attached to and depending from said sup-

porting element to engage and hold the lips 40 in distended position.

8. A lip retractor comprising a supporting element to be fastened about the head of a patient, and a pair of spaced coöperating elements adjustably attached to and depending 45 from said supporting element to engage and hold the lips in distended position.

9. A lip retractor comprising a band to be fastened about the head of a patient, a pair of spaced coöperating elements to engage 50 and hold the lips in distended position, and means for adjustably securing said coöperating elements longitudinally of and to said band.

10. A lip retractor comprising a band to 55 be fastened about the head of a patient, a supporting arm adjustably attached to and depending from said band, a member secured to and extending at an angle from the lower end of said supporting arm, and means attached to said member for engaging and holding the lip in distended position.

11. A lip retractor comprising a band to be fastened about the head of a patient, a supporting arm adjustably attached to and 65 depending from said band, a member detachably secured to and extending at an angle from the lower end of said supporting arm, and a bail removably attached to said member for engaging and holding the lip in 70 distended position.

In testimony whereof, I have signed my name to this specification, in the presence of two subscribing witnesses.

FRANK SPURR.
